UNITED STATES PATENT OFFICE.

WORTHINGTON H. INGERSOLL, OF HAMBURG, NEW JERSEY.

BOILER-TUBE SCRAPER.

SPECIFICATION forming part of Letters Patent No. 654,002, dated July 17, 1900.

Application filed January 31, 1900. Serial No. 3,428. (No model.)

To all whom it may concern:

Be it known that I, WORTHINGTON H. INGERSOLL, a citizen of the United States, and a resident of Hamburg, in the county of Sussex and State of New Jersey, have invented 5 a new and Improved Boiler-Tube Scraper, of which the following is a full, clear, and exact description.

My invention relates to that class of boiler-tube scrapers in which a shank carries a series of spring-pressed arms provided with cutting-blades or cutting edges.

The object of my invention is, first, to improve the cutting-blades so as to increase 10 their efficiency; second, to provide a strengthened construction of the shank; third, to give the arms a strong support when closed, so as to guard against the breaking of the rivets by which said arms are pivoted to the shank, 15 and, fourth, to so construct the tool that the scale and dirt will find a ready exit and will not interfere with the pivotal movement of the arms.

To these ends my invention consists in the 20 particular construction and arrangement of parts fully described hereinafter and particularly pointed out in the appended claims.

Reference is to be had to the accompanying drawings, forming a part of this specification, 25 in which similar characters of reference indicate corresponding parts in all the figures.

Figure 1 is a perspective view of my improved boiler-tube scraper. Fig. 2 is a longitudinal section thereof on line 2 2 of Fig. 3, 30 and Fig. 3 is a cross-section of the shank on line 3 3 of Fig. 2.

The shank A has at its rear end a screw-threaded reduced portion A', upon which is adapted to screw the pipe B, by means of 35 which the scraper is operated in the usual manner. Adjacent to the screw-thread the shank has a beveled shoulder A² and at a distance from the front end a disk or circular flange A³, provided at intervals with through- 40 apertures A⁴ and having its front surface A⁵ preferably inclined somewhat in a forward direction from its outer edge to the center. In the rear of the disk A³, between the apertures A⁴ thereof, are located ribs A⁶, L-shaped 45 in end view (see Fig. 3)—that is, each rib is double and consists of two members conver-

ging toward the shank. Opposing members of adjoining ribs are parallel with each other. On the other or front face of the disk A³ are located other ribs or lugs A⁷, likewise L-shaped 55 in end view and having parallel opposing members—that is, these lugs A⁷ are located in the exact continuation of the ribs A⁶, in the same planes therewith. They differ from the said ribs in length and also by the fact that 60 while the lugs A⁷ increase in width from the disk A³ to their free ends the width of the ribs A⁶ is decreased gradually, as shown in Figs. 1 and 2. The shank at its front end terminates in a polygonal tapering core A⁸. 65

Between opposing parallel lugs A⁷ are pivoted, by means of rivets C passing through said lugs, the arms D, generally four in number. These arms have on their inner faces and slightly in front of the pivots shoulders 70 D', against which bear the rear ends of springs E, the front ends of which engage the front portions of the arms at their inner faces, the front ends of the springs passing through openings D² in flanges D³, projecting inward 75 from the arms. As shown in Fig. 2, the flanges D³ of two arms are in advance of the flanges of the other two arms and by overlapping these flanges prevent the return of soot and scale. The springs E, between their 80 points of engagement with the arms D, are in contact with the tapering core A⁸. The front edges D⁴ of the arms D are rounded.

On the outer surfaces of the arms D are provided recesses for the reception of the chilled 85 cutting-blades F. These blades are given a much sharper and more efficient edge than in the construction used heretofore by making their front surfaces F' inclined rearwardly from their outer edges toward the arms, so 90 that the cutting edge F² will be in advance of the point of attachment of the blade to the arm. Each arm has a central front rib D⁵, the rear end of which comes in engagement 95 with the corresponding blade F and is inclined inward and rearward like the front face of said blade, and, further, each arm D has a central rear rib D⁶, the front end of which is substantially perpendicular to the arm and abuts against a central rib F³ on the blade F. 100 The blade is attached to the arm D by means of four lugs F⁴, two in front of the cutting

edge and two in the rear thereof, these lugs being countersunk in the outer surface of the arms D and secured thereto by screws G.

The arms D have rear end surfaces D⁷, which are adapted to lie flat against the surface A⁵ of the disk A⁸ when the arms are closed—that is, when they are brought together at their frontends—so that the arms in this position have an extended bearing on the disk A⁸ and are well braced by it, thus relieving the rivets C of excessive strain and preventing their breakage.

The openings A⁴ allow any scale or dirt loosened by the blades F and reaching the rear end of the tool to pass through the disk A⁸, so that the joints at the pivots C will not become clogged. The ribs A⁶ give the disk A⁸ the necessary strength to resist any pressure exerted by the arms D against the front face A⁵. The attachment of the blades F to the arms by means of four lugs F⁴ is very strong. The particular construction of the blades with an undercut edge renders them exceedingly efficient.

Having thus described my invention, I claim as new and desire to secure by Letters Patent—

1. A boiler-tube scraper, comprising a shank having a transverse disk, a tapering core in advance of the disk, lugs extending length-

wise of the core in advance of the disk, ribs extending rearwardly from the disk in longitudinal alinement with the said lugs, the disk being apertured between the ribs and the lugs, and having a beveled front surface, scraping- 35 arms pivoted between the lugs and having heels adapted to engage the beveled surface of the disk, interrupted longitudinal central ribs on the outer surfaces of said arms, blades secured to the arms between the sections of 40 said ribs and provided with central ribs registering with those of the arms, and springs engaging said arms and the tapered core.

2. A boiler-tube scraper, comprising a shank, 45 arms movably connected therewith, and blades secured to said arms and each provided with a transverse cutting edge, and also with four attaching-lugs, two in front of the cutting edge and two in the rear thereof, these lugs and blades being countersunk in the 50 outer surface of the arms, and fastening devices, such as screws, passing through said lugs and into the arms.

In witness whereof I have signed my name to this specification in the presence of two sub- 55 scribing witnesses.

WORTHINGTON H. INGERSOLL.
